UNITED STATES PATENT OFFICE.

JOHN C. QUINN, OF NEW YORK, N. Y., ASSIGNEE, BY MESNE ASSIGNMENTS, TO THE ENGINEER COMPANY, A CORPORATION OF NEW YORK.

REGULATION OF FURNACES.

No. 819,672.

Specification of Letters Patent.

Patented May 1, 1906.

Application filed August 3, 1904. Serial No. 219,732.

To all whom it may concern:

Be it known that I, JOHN C. QUINN, a citizen of the United States, residing in the borough of Brooklyn, city of New York, State of New York, have invented certain new and useful Improvements in Regulation of Furnaces, of which the following is a specification.

A primary object of this invention is automatically to maintain in the fire-chamber of a forced-draft furnace a uniform or substantially uniform pressure that may be equal or substantially equal to that of the atmosphere of the furnace-room or such other substantially uniform pressure as may be desired.

The purpose is to obtain maximum efficiency, economy or fuel consumption, and minimum liability of injury to the furnace or associated parts by inrush of cold air when the door of the fire-box is opened.

In the accompanying drawings, Figure 1 is a vertical longitudinal section indicating a steam-boiler furnace to which this invention is applied. Fig. 2 is a detail sectional view, on a large scale, of a diaphragm-motor; and Fig. 3 is a detail elevation, partly in section, showing a modification.

a indicates a draft-blower driven by an engine b, supplied by steam direct from the boiler through a pipe-connection c, which contains two steam-cocks d e, a steam-regulating valve f, located between them, and a steam-gage g, beyond which the steam-pipe passes to the engine b, of which h is the exhaust. A by-pass pipe connection i, containing a valve or steam-cock k, is connected around the parts d e f g. Air from the blower passes through duct m into the ash-pit n. The products of combustion pass out through flue o, in which is located the damper p. (Shown by dotted lines.) The axis of the damper has applied to it a lever-arm q, provided with an adjustable weight r on one side of the axis, and having its end on the opposite side operatively connected with a vertically-movable rod s, attached to a damper-motor t. This motor may be of the expandable and collapsible diaphragm type, as indicated in Fig. 2, or of the water-seal type, as indicated in Fig. 3, and in either case it is connected on its opposite side by a pipe or passage u of sufficient cross-sectional area with the interior of the fire-box, preferably

under the boiler-tubes and above the line of the fuel lying upon the grate.

v is the door of the fire-box, and v' is the door of the ash-pit. The play of the lever-arm q, that operates the stack-damper, may be limited by pins adjustably placed in an apertured block or frame w and against which the arm plays.

The steam-cocks d e may be used to throttle the steam; but primarily they are intended for closing the passage when inspection or repair of the regulating-valve f is required. The by-pass i may permit at all times a minimum amount of steam to be passed to the engine b, or the steam-cock k may after the parts are in operation be completely closed. The steam-regulating valve f is of such character that the amount of steam that passes it is determined by the pressure of the steam. The speed of the blower will therefore be controlled relatively to the boiler-pressure, so that at all times the desired volume and pressure of air will be delivered to the furnace.

In order to regulate or control the pressure within the fire-box above the fuel, the present invention contemplates that the discharge of the products of combustion from the furnace shall be controlled by the pressure within the fire-box. In the present instance this mode of control is shown as accomplished by controlling the damper in the stack correspondingly with variations of pressure in the fire-box. The invention, however, is not in its broadest aspect limited to this particular mode of control nor to the special apparatus illustrated and described. Thus if the fire-box pressure rises above the desired normal the rod s is raised and the damper correspondingly opens, and vice versa, the movements of the damper being graduated and bearing a relation to the variations of pressure in the fire-box. To afford adjustment, the rod s may be composed of two parts united by a reversely-threaded adjustable coupling or sleeve s'. (Shown in Fig. 2.) In this way, the various parts of the apparatus being properly proportioned or related to each other, a substantially uniform pressure and such pressure as is desired may be maintained in the fire-box.

I claim as my invention—

1. The combination with a steam-boiler and its furnace, of means governed by the

steam-pressure in said boiler for positively supplying air to the said furnace relatively to the steam-pressure, a damper and means governed by the pressure of the furnace-gases for controlling the damper to maintain a substantially constant predetermined pressure in said furnace.

2. The combination with a steam-boiler and its furnace, of means governed by the steam-pressure in said boiler for positively supplying air to said furnace relatively to the steam-pressure, and means governed by the pressure in the furnace for maintaining a substantially constant predetermined pressure in said furnace.

3. The combination with a steam-boiler and its furnace, of means governed by the steam-pressure in said boiler for positively supplying air to said furnace relatively to the steam-pressure, a damper and means for controlling the damper to maintain a substantially constant predetermined pressure in said furnace, such means being automatically operated independent of the steam-pressure.

4. The combination with a steam-boiler 25 and its furnace, of means governed by the steam-pressure in said boiler for positively supplying air to said furnace, relatively to the steam-pressure, and means actuated by variations of pressure within the furnace 3- to control the discharge of products of combustion and thereby maintain a substantially uniform pressure within the furnace.

5. The combination with a furnace, and a steam-boiler, of a blower for supplying air to the furnace governed by the pressure of steam within the boiler, and a damper controlling the exit of gases from the furnace, said damper being governed by the pressure of the furnace-gases. 35 40

In testimony whereof I have hereunto subscribed my name.

JOHN C. QUINN.
